US0D1083130S

(12) **United States Design Patent** (10) **Patent No.:** **US D1,083,130 S**
(45) **Date of Patent:** **** Jul. 8, 2025**

(54) **FACIAL TREATMENT DEVICE**

(71) Applicant: **Therabody, Inc.**, Los Angeles, CA (US)

(72) Inventors: **Jason Wersland**, Los Angeles, CA (US); **Benjamin Nazarian**, Beverly Hills, CA (US); **Jaime Sanchez Solana**, Los Angeles, CA (US); **Eduardo Merino**, Los Angeles, CA (US); **Bill Webb**, San Francisco, CA (US); **Alex Zhu**, Xianmen (CN)

(73) Assignee: **Therabody, Inc.**, Los Angeles, CA (US)

(**) Term: **15 Years**

(21) Appl. No.: **29/913,854**

(22) Filed: **Oct. 10, 2023**

Related U.S. Application Data

(63) Continuation of application No. 29/813,195, filed on Oct. 27, 2021, now Pat. No. Des. 1,004,793, which is a continuation-in-part of application No. 29/772,505, filed on Mar. 2, 2021, now Pat. No. Des. 976,431.

CLAIM

The ornamental design for a facial treatment device as shown and described.

DESCRIPTION

FIG. 1 is a top perspective view of a facial treatment device showing the claimed design;

FIG. 2 is front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the figures show portions of the facial treatment device that form no part of the claimed design.

1 Claim, 6 Drawing Sheets
